LOOM

Application filed October 10, 1928. Serial No. 311,549.

This improvement relates to looms and is particularly intended to provide a simple and reliable construction and arrangement by the use of which the loom is automatically prevented from continuing to weave, either after the filling threaded has broken or after the filling package in the shuttle has approached the point of exhaustion.

The present improvement resides in a combination of a feeler mechanism with a weft fork mechanism in such a way that each independently, as occasion arises, acts to knock off the shipper lever or control lever to cause the stoppage of the loom.

15 This and other features of the invention will be described in the following specification and will be defined in the claims hereto annexed.

In the accompanying drawing I have illustrated a simple and convenient form of mechanism for accomplishing the cessation of weaving by the stoppage of the loom through the control of the associated feeler and weft fork mechanism.

25 Fig. 1 is a plan view of the assembled mechanism in association with the loom control or shipper lever and a knock off arm.

Fig. 2 is a front elevation of the mechanism shown in Fig. 1.

30 Fig. 3 is an end view showing that part of the mechanism directly associated with the weft hammer.

Fig. 4 is an end elevation partly in cross section showing the feeler actuated rock shaft through which the weft hammer is made operative upon the weft fork slide.

Fig. 5 is a cross section through the shuttle box and shuttle.

At the front of the loom in the usual position is mounted the horizontal plate 1 having a slot 1^a extended transversely of the loom and provided at its inner end with a notch or recess with which the upwardly projecting shipper or loom control arm 2 is engaged to keep it from loom-stopping position. As is well known to those skilled in the art, when the arm 2 is pushed out of its engaging notch or recess into the main portion of the slot it is automatically moved under the influence of a spring or weight toward the left hand end

of the loom to stop the loom, either through the slipping of the driving belt from the driving pulley to the loose pulley or, in the case of an electrically driven loom, throwing a clutch, or a switch to break the circuit. These details are not illustrated as they are well known in the art.

At the left hand end of the plate 1, directly in line with a lateral opening or window through the side of the shuttle box and through the side of the shuttle contained therein, is mounted a reciprocatory feeler finger 4. The shuttle 7 carries the usual supply or filling bobbin 7^a and, when correctly seated between the movable swell 6^a and the opposite side wall 6 of the shuttle box mounted on the lay, positions the base portion of the bobbin which in this case is slotted diametrically to receive the thin feeler finger 4, so that with each forward movement of the lay toward the feeler the tip of the feeler penetrating the side of the shuttle engages the filling yarn wound on the base. So long as the slot in the bobbin is covered with the coiled yarn its engagement with the feeler serves to move the feeler forwardly with the advancing lay, thereby moving a latch mounted on the weft fork slide out of the path of the corresponding portion of the weft hammer as will presently be described.

The feeler is normally pressed rearward by a gravity actuated rock shaft and is mounted in bearings formed in two upstanding lugs 3^a and 3^b forming part of the feeler bracket 3 adjustably secured to the plate 1. At right angles to the feeler 4 and somewhat above the level thereof is mounted a rock shaft 30 which is carried in upright bearing brackets 8^c and 10^a. Between the bearing bosses 3^a and 3^b the feeler 4 is provided with a vertically grooved collar engaged by a forked arm 31, which is secured to the rock shaft by a suitable hub or collar so as to cause the shaft 30 to rock when the feeler actuated arm 31 is moved forwardly by the advancing lay.

At its inner end, beyond the bearing bracket 10^a, the rock shaft is bent to form an angular extension 14^a to which is detachably secured a weight block 14 in line with a finger 13^a projecting rearwardly and up-

wardly from the latch 13, which is pivotally mounted in a bearing boss 11^a formed on the forward portion of the weft fork slide or holder 11. The rearward end of the pivotal latch 13 is positioned to be engaged by a projecting member 21 on the vibratory weft hammer 19. Normally, the parts are in the position shown in Fig. 3, but as the lay moves forward and the filling yarn on the bobbin 10 engages the tip of the feeler the latter is pushed forward also causing a partial rotation in a clockwise direction, as seen in Fig. 3, whereby the latch-actuating end of the rock shaft is caused to lift the finger 13^a and rock the latch 13 out of registry with the bunt 25 15, so that no movement of the weft fork holder 11 is produced.

On the other hand, when the filling is unwound sufficiently to uncover the slot in the side of the bobbin 7^a so as to allow the feeler tip to enter therein, the actuation of the feeler does not occur and therefore the latch 13 remains in its normal position to be engaged by the member 21 of the weft hammer. This causes a forward movement of the weft fork holder 11, which is provided with a lateral depending boss 11^c near its forward end arranged to engage the right hand end of the knock off lever 15 which is pivoted at 15^a 30 to the loom and whose other end is in position to press the lever 2 out of its retaining recess, thereby allowing the lever 2 to move to loom-stopping position.

The operation of the weft fork is well known. On the rear end of the weft fork holder 11 is pivoted in an elongated slot or opening the usual weft fork 12 on a pivot pin 12^b, whose downwardly extending tines are in position to be engaged by the last shot 40 of filling carried across the lay by the shuttle. The forward end of the weft fork has the usual hook 12^a in registry with a projection 20 on the weft hammer 19, so that whenever the projection 20 of the weft hammer 45 engages the hook 12^a the forward movement of the weft hammer causes the weft fork-holder 11 to move forward thereby actuating the knock off lever 15, as above described. So long as the last shot of filling 50 from the shuttle remains unbroken, the weft fork will be tipped downwardly on the forward movement of the lay, thus tipping up the hook 12^a out of registry with the projection 20 on the weft hammer. If the filling 55 yarn breaks, however, the weft fork is not actuated and therefore the weft hammer operates by the mechanism described to stop the loom.

It will therefore be seen that the weft fork mechanism is so combined with a feeler mechanism that not only does it act to stop the loom when the filling yarn paid out from the shuttle breaks, but it also acts to stop the loom by its combined relation with the feeler device when the yarn on the filling package

is sufficiently near complete exhaustion to allow the feeler tip to remain active when the lay advances.

Obviously a similar mechanism for the right hand side of the loom will act in precisely the same way on alternate forward movements of the lay.

In the ordinary plain loom considerable time is lost and imperfect weaving is produced when for any reason a pick of filling is carried only part way through the shed formed by the warp threads. The continued operation of the loom after such an occurrence renders it necessary for the weaver, when this condition is observed by him, to remove the picks of filling in front of such partial pick.

This prevents lost time and labor and insures more perfect weaving by affording automatic protection against continuance of weaving until the filling package is exhausted and leaves a partial pick of filling in the fabric, which has to be removed to avoid imperfections.

The rock shaft 30 serves as an actuator shaft for advancing or projecting the feeler toward the filling, this action being secured through the weighted arm 14, which tends to rock the downwardly projecting attached feeler arm 31 toward the advancing lay on which the filling carrying shuttle is supported. Furthermore, as the arm 14, as best shown in Fig. 3, in its normal undisturbed position lies with its toe or free end directly above the depressed rearward end of the latch 13, it serves when in such normal position to prevent accidental displacement of the latch which would carry it out of engaging position with the forwardly projecting portion 21 of the weft hammer, besides insuring the positive lowering of the latch into the path of the weft hammer. On the other hand, when the rock shaft 30 is reversely rotated by the filling induced movement of the feeler the arm 14 will positively engage the finger 13^a forming part of the latch 13 and will insure the movement of the rear end of the latch out of engagement position with the vibratory hammer 19, so that it will be seen that the arm 14 has a two-way engagement with the latch which transmits, or fails to transmit, the forward movement of the hammer to the loom-stopping slide 11.

The above arrangement not only makes the device fool proof against accident, but it has the further advantage of maintaining the controlling mechanism under a constant and uniform pressure by gravity action instead of opposing a spring resistance, which is more or less variable anyway and which unduly increases in strength as the feeler is pressed back by the advancing filling package.

What I claim is:

1. In a loom-stop mechanism, the combina-

tion with a freely slidable shuttle-penetrating filling feeler arranged in front of the filling containing shuttle, a gravity actuated rock shaft at the front of the loom connected with said feeler to normally project the feeler into the path of the advancing filling and itself to be reversely rocked by the filling-induced movement of the feeler, a loom-stop motion embracing a weft fork, a supporting slide and an actuating vibratory hammer, a latch mounted on said slide to be engaged by said hammer to actuate the slide to loom-stopping position independently of the weft fork, said rock shaft being provided with an arm having a two-way actuating engagement with said latch to insure the movement of the latch into and out of the path of the vibratory hammer.

2. In a loom-stop mechanism, the combination with a freely movable shuttle-penetrating filling feeler arranged in the path of the forwardly advancing filling, a gravity actuated, feeler-actuating rock shaft mounted at the front of the loom to normally project the feeler toward the advancing filling and itself reversely rocked by the feeler when moving forward under the push of the advancing filling, an arm secured to said rock shaft, a weft stop mechanism embracing a weft fork itself, supporting slide and an actuating vibratory hammer, a latch pivotally mounted on said slide forwardly of the weft fork to present its rear end in the path of said hammer, said latch being provided with a projecting finger, said arm on said rock shaft being disposed in one position to prevent the movement of said latch out of the path of the weft hammer and when reversely rocked by filling-induced movement of the feeler to engage said finger and move the latch out of the path of said hammer.

In witness whereof, I have subscribed the above specification.

JOHN S. COLDWELL.
